TUNING SELECTIVITY CONTROL CIRCUIT

Paul O. Farnham, Boonton, N. J., assignor to
Radio Corporation of America, a corporation of
Delaware

Application May 25, 1935, Serial No. 23,445

2 Claims. (Cl. 250—20)

My present invention relates to tuning circuits for radio receivers, and more particularly to novel circuits for controlling the tuning of superheterodyne receiving systems so as to increase the apparent sharpness of tuning.

In radio receiving systems of the superheterodyne type, the latter being substantially universally employed for radio reception at the present time, it is desirable to have the signal selector network of the system increase in apparent selectivity as the system is tuned to resonance with a given broadcasting station. This is especially true of high fidelity receivers, since in the latter the listener finds it particularly annoying to listen to distortion fringes of the accepted band of frequencies. The ideal selectivity characteristic of a receiver is one wherein the response of the system is substantially zero at the limits of the desired band, and the sides of the resonance curve are steep and substantially parallel; the band being sufficiently wide, of course, to substantially uniformly transmit to the demodulator all the reproducible audio frequencies.

It may, therefore, be stated that it is an important object of this invention to provide a selectivity control network for a radio receiver of the superheterodyne type wherein the sharpness of tuning of the receiver is increased by phase opposition of intermediate and signal carrier frequency effects through a double function stage.

Another important object of this invention is to provide in a superheterodyne type of receiver a frequency changer network disposed between the signal input element and the intermediate frequency amplifier, the frequency changer network comprising a pair of tubes arranged in cascade and each of them being coupled to a local oscillator so that each tube acts as a first detector; signal and intermediate frequency circuits being arranged between the cascaded tubes to increase the apparent sharpness of tuning of the receiver as it is tuned through the tuning range.

Still other objects of the invention are to improve generally the efficiency and tuning of superheterodyne receivers, and more especially to provide improved tuners in an economical and simple manner in such receivers.

The novel features which I believe to be characteristic of my invention are set forth in particularity in the appended claims, the invention itself, however, as to both its organization and method of operation will best be understood by reference to the following description taken in

connection with the drawing in which I have indicated diagrammatically a circuit organization whereby my invention may be carried into effect.

In the drawing:

Fig. 1 is a circuit diagram of a superheterodyne receiver embodying the invention,

Fig. 2 graphically shows the effect of the invention.

Referring now to the circuit diagram in Fig. 1, it is to be noted that the receiving system shown includes conventional networks with the exception of that portion of the system which embodies the invention. The receiver is a superheterodyne of the multi-range type, and includes a signal collector A which may be the usual grounded antenna, a loop, or any other known type of collector. While the collector may be followed by one, or more, stages of tunable radio frequency amplification prior to the first detector, the signal amplifiers have been omitted to preserve simplicity of disclosure. The first detector network comprises a pair of cascaded tubes 1, 2; each of these tubes being of the pentode type and being fed with local oscillations from a local oscillator 3. The intermediate frequency energy produced in the output circuit 4 of tube 2 is amplified in the I. F. amplifier 5. The output of the latter is demodulated in a second detector 6; the demodulated signal energy is then amplified in one, or more, audio amplifiers, and finally reproduced in any desired type of reproducer.

The usual AVC network is employed to overcome fading effects; the volume control arrangement is schematically represented since those skilled in the art are fully aware of the manner of constructing such an arrangement. For example, the AVC arrangement shown by Stuart Ballantine in application Serial No. 376,163, filed July 5, 1929, Patent No. 2,046,237, June 30, 1936, may be used. The control bias produced by the AVC rectifier may be used to vary the gain of the I. F. amplifier 5, and also the gain of each of the first detector tubes 1 and 2. The lead 7, designated "AVC", is connected to the signal grids of tubes 1, 2 and the grid circuits of the tubes of network 5.

Considering, now, the networks including the present invention, the tube 1 functions as a first detector to produce I. F. energy and as an amplifier of signal energy. The signal input circuit comprises a coil 8 and a variable tuning condenser 9 connected in parallel. The coil 8 is tapped to provide several tuning ranges, and the tap 10 is adjusted to change the operating tuning range of the set. This is a well known and con-

ventional device, and need not be described any further. The collector A and the signal grid of tube 1 are connected to the high alternating potential side of the signal input circuit. The 5 low alternating potential side of coil 8 is grounded through a condenser 11. The AVC lead 7 is connected to the junction of coil 8 and condenser 11 through a filter resistor 12.

The cathode of the tube 1 has the locally 10 produced oscillations of the local oscillator 3 impressed upon it. The oscillator is of a conventional type, and has its anode regeneratively coupled to the low alternating potential side of coil 13 through condenser 14. The coil 13 is provided with the range switching device described above. The oscillator tuning condenser 15 has its 15 rotor mechanically coupled with the rotor of the condenser 9. The cathode circuit of oscillator tube 3 includes the grounded bias resistor 16; the cathode side of resistor 16 is connected by 20 lead 17 to the cathode of tube 1. Thus, in the absence of AVC action, normal signal grid bias for tubes 1 and 2 is derived from the voltage drop across resistor 16.

The tube 1 has its plate energized from a source 25 of direct current voltage B (not shown) through a coil 17''. The latter coil is part of the output network which is resonated to the operating intermediate frequency. The tuning condenser for 30 the I. F. network is designated by numeral 18, and the condenser has one side thereof connected to the plate side of coil 17''. The other side of the condenser is connected to ground through a path including coil 19 and condenser 20. A variable 35 tuning condenser 21, similar in construction to condenser 9, is connected across coil 19 and condenser 20. The coil 19 and condenser 21 comprise a circuit capable of being tuned to the same signal frequencies as the circuit 8-9 is 40 tuned to. The coil 19 has a wave band switching device operatively associated therewith.

The tube 2 includes in its input two networks 45 similar in construction to network 18-17'' and network 19-21. Thus, coil 22 is magnetically coupled to coil 17'', and is connected between the signal input grid of tube 2 and ground. Condenser 23 tunes coil 22 to the operating intermediate frequency, the condenser being connected on one side thereof to the grid side of 50 coil 22. The condenser 23 is connected to ground through coil 24 and condenser 20. The variable condenser 25, similar in construction to condensers 9 and 21, is connected in shunt with coil 24. The network 25-24 is tunable to the same 55 signal frequencies as network 19-21, and coil 24 has a wave band switching device operatively associated therewith. The rotors of variable condensers 21 and 25 are arranged to be uncontrolled, as shown by the dotted lines, with those of condensers 9 and 15.

The AVC lead 7 is connected to the grid circuit of tube 2 through filter resistor 12' and coil 60 22. Of course, the adjustable taps of the wave band switching devices of the several tunable circuits may be arranged for simultaneous mechanical actuation; those skilled in the art are fully aware of such a construction. The plate circuit of detector tube 2 includes the network 4 which is resonated to the operating intermediate frequency. By means of tuned circuit 4', coupled to circuit 4 as at M₁, the I. F. energy is impressed upon the amplifier 5. The AVC lead 7 is connected to the signal grid circuits of amplifier 5 through filter resistor 40.

The local oscillator is connected to the first 5 detector tube 2 by connecting the cathode side of resistor 16 to the cathode of tube 2 through lead 17'. In operation, the tubes 1 and 2 are used as first detectors by injecting the local oscillator voltage into their input circuits. Signal energy of a desired frequency, chosen from a selected wave band, is impressed upon detector tube 1. However, in the output circuit of tube 1 there is caused to exist I. F. energy, equal to the 10 difference of the oscillator and signal frequencies, and energy of signal frequency. In other words there is transferred from the output circuit of tube 1 to the input electrodes of detector tube 2 energy of intermediate and signal frequency. It 15 will now be seen that tube 1 functions both as a first detector and as a carrier wave amplifier. Tube 2 functions as a first detector and as an intermediate frequency amplifier.

The intermediate frequency energy output 20 from tube 2 will depend upon both the I. F. and signal frequency input to tube 2, both as to amplitude and phase. At resonance these two inputs will be of such phase as to aid in producing the I. F. energy output in the plate circuit 25 of tube 2. Off resonance, on the other hand, the phase of the signal frequency will advance, while that of the I. F. will be retarded; thus producing cancellation in the output of tube 2 when the total phase displacement reaches "pi" and the 30 amplitudes are such as to give approximate equal intermediate frequency outputs from tube 2. The coils 17'' and 22 should have negative mutual inductance when the signal circuits directly below them are coupled by capacity 20 35 as shown. If the coils 19 and 24 of the signal circuits are coupled together magnetically instead of using coupling capacity 20, then the sense of the magnetic coupling between the coils 19 and 24 should be the same as that between I. F. coils 40 17'' and 22.

A consideration of the comparative selectivity curves shown in Fig. 2 will graphically demonstrate the utility of the present invention. The full line curve A shows the selectivity of the 45 signal circuits from the input of tube 1 to the output of tube 2, when the present invention is not embodied in the receiver. However, the dotted line curve C shows the manner in which the selectivity curve of the whole system from the 50 input of tube 1 to the output of tube 2 is altered, when the present invention is utilized. The curve C is characterized by its steeper sides near resonance.

While I have indicated and described a system 55 for carrying my invention into effect, it will be apparent to one skilled in the art that my invention is by no means limited to the particular organization shown and described, but that many modifications may be made without departing 60 from the scope of my invention, as set forth in the appended claims.

What I claim is:

1. A superheterodyne receiver comprising a 65 pair of first detector tubes arranged in cascade, a local oscillator connected to the pair of first detector tubes to impress the locally produced oscillations thereupon, a signal input circuit connected between the input electrodes of the prior one of said first detector tubes, a network tuned 70 to the operating intermediate frequency in the output circuit of the following of said first detector tubes, and a network coupling the output circuit of the prior detector tube to the input circuit of the following detector tube, said last 75

named network comprising at least one circuit tuned to the intermediate frequency and one circuit tuned to the frequency of the signal input circuit of said prior detector tube, the constants of the circuits of said coupling network being so chosen that at resonance the signal and intermediate frequency inputs to the following one of said detector tubes are of such phase as to aid in producing the intermediate frequency energy in the output of said following detector tube.

2. A superheterodyne receiver including a first detector tube provided with a signal input circuit, an intermediate frequency output circuit and a local oscillator coupled to the first detector tube

to impress local oscillations thereon, the receiver being characterized by the inclusion of a second tube in cascade with the first detector tube, and a coupling network between the first detector tube and the input circuit of said second tube, said coupling network including a circuit tuned to the operating intermediate frequency and a circuit tuned to the desired signal frequency, means impressing the local oscillations on the second tube, and an intermediate frequency output circuit connected to the output electrodes of the second tube.
